Des. 240,122
Patented June 1, 1976

240,122

FISHING SIGNAL

Theodore Montgomery, Box 43, and Wayne T. Wise,
Box 175, both of Frankfort, S. Dak. 57440

Filed Mar. 6, 1975, Ser. No. 555,744

Term of patent 14 years

Int. Cl. D10—06; D26—02

U.S. Cl. D10—114

FIG. 1 is a view in perspective as seen from one side, the front and above of a fishing signal showing our new design;

FIG. 2 is a view in side elevation thereof illustrating the side shown in FIG. 1;

FIG. 3 is a view in side elevation thereof of the side opposite that shown in FIG. 2;

FIG. 4 is a view in top plan thereof;

FIG. 5 is a view in bottom plan thereof;

FIG. 6 is an elevational view of the front end thereof; and

FIG. 7 is an elevational view of the rear end thereof.

We claim:

The ornamental design for a fishing signal, substantially as shown.
